Primary Examiner — T Chase Nelson*Assistant Examiner* — Rachel Wolfe(74) *Attorney, Agent, or Firm* — Matthias Scholl P.C.;
Matthias Scholl(57) **CLAIM**

The ornamental design for a lampshade for flameless candle, as shown and described.

DESCRIPTION

FIG. 1 is a front elevation view of a lampshade for flameless candle;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof; and,

FIG. 7 is a perspective view thereof.

The broken lines depict portions of the lampshade for flameless candle that form no part of the claimed design.

1 Claim, 7 Drawing Sheets(56)
